(57) **ABSTRACT**

Disclosed herein is a coil component that includes a winding core part and first and second wires wound around the winding core part. The first and second wires constitute at least three winding layers on the winding core part. The same turns of the first and second wires are positioned in mutually different winding layers over a plurality of turns.

COIL COMPONENT

BACKGROUND OF THE INVENTION

Field of the Invention

The present invention relates to a coil component and, more particularly, to a coil component in which a wire is wound around a winding core part thereof in multiple layers.

Description of Related Art

To increase the inductance of a coil component in which a wire is wound around a winding core part thereof, it is necessary to increase the number of turns of the wire. However, when the wire is wound around a winding core part in a single layer, the length necessary for the winding core part is increased in proportion to the number of turns. Thus, in order to increase the number of turns of the wire while suppressing an increase in the length of the winding core part, the wire needs to be wound around the winding core part in multiple layers as described in JP 1999-74133A.

Meanwhile, the coil component mainly used in a power supply circuit is required to provide low DC resistance and high rated current. In order to satisfy the requirements, it is conceivable to use a method of using two wires connected in parallel. For instance, JP 1999-74133A discloses, in FIGS. 6 to 8, a coil component using two wires wound in multiple layers.

However, in the winding structure disclosed in JP 1999-74133A (FIGS. 6 to 8), the same turns of two wires are always adjacently disposed, reducing the degree of freedom of winding work.

SUMMARY

It is therefore an object of the present invention to enhance the degree of freedom of winding work in a coil component in which two wires are wound in multiple layers.

A coil component according to the present invention includes a winding core part and first and second wires wound around the winding core part. The first and second wires constitute at least three winding layers on the winding core part, and the same turns of the first and second wires are positioned in mutually different winding layers over the plurality of turns.

According to the present invention, the same turns of the first and second wires are positioned in mutually different winding layers over the plurality of turns, so that the degree of winding work can be enhanced.

In the present invention, the at least three winding layers may include a lower layer closest to the winding core part, an upper layer farther away from the winding core part than the lower layer, and at least one intermediate layer positioned between the lower and upper layers. The lower layer may include the first wire, the upper layer may include the second wire, and the intermediate layer may include the first and second wires in a mixed manner. With this configuration, the difference in turn number between adjacent turns is reduced, allowing a parasitic capacitance component to be suppressed.

In the present invention, the first wire may be continuously wound in the lower layer in an aligned state, the second wire may be continuously wound in the upper layer in an aligned state, and the first and second wires may be alternately wound in the intermediate layer. With this configuration, it is possible to obtain a structure in which the

2

first and second wires are disposed in an aligned state in the lower and upper layers, respectively.

In the present invention, i-th turn (i is an integer equal to or larger than 5) and (i-th+1) turn of the first wire may be wound in the lower layer, (i-th+2) turn of the first wire and (i-th+1) turn of the second wire may be wound in the intermediate layer, and i-th turn and (i-th+2) turn of the second wire may be wound in the upper layer. With this configuration, by repeatedly forming a winding pattern including i-th to (i-th+2) turns of the first and second wires, a regular winding structure including three winding layers can be obtained.

In this case, (i-th+2) turn of the first wire may be wound along a valley line formed by the i-th turn and (i-th+1) turn of the first wire. With this configuration, (i-th+2) turn of the first wire can be supported by i-th turn and (i-th+1) turn of the first wire.

Further, in this case, (i-th+3) turn of the second wire may be wound along a valley line formed by (i-th+2) turn of the first wire and (i-th+1) turn of the second wire, and (i-th+4) turn of the second wire may be wound along a valley line formed by (i-th+1) turn and (i-th+3) turn of the first wire. With this configuration, (i-th+3) turn of the second wire can be supported by the valley line formed by (i-th+2) turn of the first wire and (i-th+1) turn of the second wire, and (i-th+4) turn of the second wire can be supported by the valley line formed by (i-th+1) turn and (i-th+3) turn of the first wire.

In the present invention, the intermediate layer may include a first intermediate layer positioned on the lower layer side and a second intermediate layer positioned on the upper layer side, and, whereby, the first and second wires may constitute at least four winding layers.

In the present invention, the first wire may be continuously wound in the lower layer in an aligned state, the second wire may be continuously wound in the upper layer in an aligned state, and first and second wires may be alternately wound in the first and second intermediate layers. With this configuration, in a winding structure including four winding layers, the first and second wires can be regularly disposed in the first and second intermediate layers.

In this case, i-th turn (i is an integer equal to or larger than 8) and (i-th+1) turn of the first wire may be wound in the lower layer, (i-th+2) turn of the first wire and (i-th+1) turn of the second wire may be wound in the first intermediate layer, (i-th+3) turn of the first wire and (i-th+2) turn of the second wire may be wound in the second intermediate layer, and i-th turn and (i-th+3) turn of the second wire may be wound in the upper layer. With this configuration, by repeatedly forming a winding pattern including i-th to (i-th+3) turns of the first and second wires, a regular winding structure including four winding layers can be obtained.

Further, in this case, (i-th+3) turn of the first wire may be wound along a valley line formed by (i-th+2) turn of the first wire and (i-th+1) turn of the second wire. With this configuration, (i-th+3) turn of the first wire can be supported by (i-th+2) turn of the first wire and (i-th+1) turn of the second wire.

Further, in this case, (i-th+4) turn of the second wire may be wound along a valley line formed by (i-th+3) turn of the first wire and (i-th+2) turn of the second wire, (i-th+5) turn of the second wire may be wound along a valley line formed by the i-th turn and (i-th+1) turn of the first wire, and (i-th+6) turn of the second wire may be wound along a valley line formed by (i-th+2) turn of the first wire and (i-th+5) turn of the second wire. With this configuration, (i-th+4) turn of the second wire can be supported by the valley line formed by

(i-th+3) turn of the first wire and (i-th+2) turn of the second wire, (i-th+5) turn of the second wire can be supported by the valley line formed by the i-th turn and (i-th+1) turn of the first wire, and (i-th+6) turn of the second wire can be supported by the valley line formed by (i-th+2) turn of the first wire and (i-th+5) turn of the second wire.

In the present invention, the first wire may be continuously wound in the lower layer and first intermediate layer in an aligned state, and the second wire may be continuously wound in the upper layer and second intermediate layer in an aligned state. With this configuration, in a winding structure including four winding layers, the first wire can be wound in the lower layer and first intermediate layer in an aligned state, and the second layer can be wound in the upper layer and second intermediate layer in an aligned state.

In this case, i-th turn (i is an integer equal to or larger than 5) and (i-th+2) turn of the first wire may be wound in the lower layer, (i-th+1) turn and (i-th+3) turn of the first wire may be wound in the first intermediate layer, i-th turn and (i-th+2) turn of the second wire may be wound in the second intermediate layer, and (i-th+1) turn and (i-th+3) turn of the second wire may be wound in the upper layer. With this configuration, by repeatedly forming a winding pattern including i-th to (i-th+3) turns of the first and second wires, a regular winding structure including four winding layers can be obtained.

Further, in this case, (i-th+3) turn of the first wire may be wound along a valley line formed by the i-th turn and (i-th+2) turn of the first wire, and (i-th+3) turn of the second wire may be wound along a valley line formed by the i-th turn and (i-th+2) turn of the second wire. With this configuration, (i-th+3) turn of the first wire can be supported by the valley line formed by the i-th turn and (i-th+2) turn of the first wire, and (i-th+3) turn of the second wire can be supported by the valley line formed by the i-th turn and (i-th+2) turn of the second wire.

Further, in this case, (i-th+4) turn of the second wire may be wound along a valley line formed by (i-th+1) turn and (i-th+3) turn of the first wire, and (i-th+5) turn of the second wire may be wound along a valley line formed by (i-th+2) turn and (i-th+4) turn of the second wire. With this configuration, (i-th+4) turn of the second wire can be supported by the valley line formed by (i-th+1) turn and (i-th+3) turn of the first wire, and (i-th+5) turn of the second wire can be supported by the valley line formed by (i-th+2) turn and (i-th+4) turn of the second wire.

The coil component according to the present invention may further include a flange part and a terminal electrode provided on the flange part and connected with one ends of the first and second wires, and the one ends of the first and second wires may be short-circuited through the terminal electrode. With this configuration, the first and second wires can be connected in parallel.

As described above, the coil component according to the present invention has a winding structure having a high degree of freedom of winding work. Thus, it is possible to prevent an increase in a parasitic capacitance component due to proximity between two turns between which a difference in turn number is large.

BRIEF DESCRIPTION OF THE DRAWINGS

The above features and advantages of the present invention will be more apparent from the following description of certain preferred embodiments taken in conjunction with the accompanying drawings, in which:

FIG. 1 is a schematic perspective view illustrating the outer appearance of a coil component according to a preferred embodiment of the present invention;

FIG. 2 is a schematic perspective view illustrating the outer appearance of a coil component according to a first modification;

FIG. 3 is a schematic perspective view illustrating a state before the wire is wound around the winding core part;

FIG. 4 is a schematic perspective view illustrating the outer appearance of a coil component according to a second modification;

FIG. 5 is a schematic plan view illustrating the pattern shape of a printed circuit board on which the coil component is mounted;

FIG. 6 is a schematic cross-sectional view for explaining a first winding structure of the wires;

FIGS. 7 and 8 are schematic process diagrams for explaining a method for obtaining the first winding structure;

FIG. 9 is a schematic cross-sectional view for explaining a second winding structure of the wires;

FIGS. 10 and 11 are schematic process diagrams for explaining a method for obtaining the second winding structure;

FIG. 12 is a schematic cross-sectional view for explaining a third winding structure of the wires; and

FIGS. 13 and 14 are schematic process diagrams for explaining a method for obtaining the third winding structure.

DETAILED DESCRIPTION OF THE EMBODIMENTS

Preferred embodiments of the present invention will be explained below in detail with reference to the accompanying drawings.

FIG. 1 is a schematic perspective view illustrating the outer appearance of a coil component 1 according to a preferred embodiment of the present invention.

As illustrated in FIG. 1, the coil component 1 according to the present embodiment includes a drum-shaped core 10 having flange parts 11 and 12 and a winding core part 13, a plate-shaped core 20 fixed to the flange parts 11 and 12, a terminal electrode E1 provided on the flange part 11, a terminal electrode E2 provided on the flange part 12, and wires W1 and W2 wound around the winding core part 13. The wires W1 and W2 are each a coated conductive wire with a good conductor such as copper as a core material.

The core 10 is a drum-shaped block made of a high-permeability material such as ferrite and has a structure integrating the flange parts 11, 12 and the winding core part 13 provided therebetween. The core 20 is a plate-shaped block also made of a high-permeability material such as ferrite. The cores 10 and 20 are fixed to each other by an adhesive. One ends of the wires W1 and W2 are connected to the terminal electrode E1, and the other ends thereof are connected to the terminal electrode E2. The terminal electrodes E1 and E2 are each formed of silver paste fired on the core 10. Thus, the one ends of the wires W1 and W2 are short-circuited through the terminal electrode E1, and the other ends thereof are short-circuited through the terminal electrode E2. That is, the wires W1 and W2 are connected in parallel between the terminal electrodes E1 and E2. The reason that the wires W1 and W2 are connected in parallel is that the coil component 1 according to the present embodiment is a coil component for a power supply circuit and required to have a low DC resistance and a high rated current.

In place of the terminal electrodes E1 and E2, a terminal fitting may be used. For example, as in a coil component 2 according to a modification illustrated in FIG. 2, a terminal fitting 30 fixed to the flange part 11 and a terminal fitting 40 fixed to the flange part 12 may be used. The terminal fitting 30 is a terminal electrode fixed to the flange part 11 of the core 10 by an adhesive or the like and is connected with one ends of the wires W1 and W2, and the terminal fitting 40 is a terminal electrode fixed to the flange part 12 of the core 10 by an adhesive or the like and is connected with the other ends of the wires W1 and W2.

At the time of manufacturing the coil component 2, the terminal fittings 30 and 40 are bonded to the core 10, and then one ends of the wires W1 and W2 are connected to the terminal fitting 30. As illustrated in FIG. 3, the terminal fitting 30 in a state before wire connection has a mounting part 31, first and second wire connection parts 32 and 33, first and second welding tabs 34 and 35, first and second fixing tabs 36 and 37, and a fillet formation part 38. In a state where the one end of the wire W1 is disposed on the wire connection part 32, the fixing tab 36 is folded to thereby secure the one end of the wire W1 to the wire connection part 32, and in a state where the one end of the wire W2 is disposed on the wire connection part 33, the fixing tab 37 is folded to thereby secure the one end of the wire W2 to the wire connection part 33. In this state, the welding tabs 34 and 35 are folded and melted by heat, whereby the terminal fitting 30 and the one ends of the wires W1 and W2 are welded. Thereafter, the core 10 is rotated to wind the wires W1 and W2 around the winding core part 13. Similarly, the terminal fitting 40 in a state before wire connection has a mounting part 41, first and second wire connection parts 42 and 43, first and second welding tabs 44 and 45, first and second fixing tabs 46 and 47, and a fillet formation part 48. In a state where the other end of the wire W1 is disposed on the wire connection part 42, the fixing tab 46 is folded to thereby secure the other end of the wire W1 to the wire connection part 42, and in a state where the other end of the wire W2 is disposed on the wire connection part 43, the fixing tab 47 is folded to thereby secure the other end of the wire W2 to the wire connection part 43. In this state, the welding tabs 44 and 45 are folded and melted by heat, whereby the terminal fitting 40 and the other ends of the wires W1 and W2 are welded. Finally, the core 20 is bonded to the core 10, whereby the coil component 2 illustrated in FIG. 2 is completed.

In the coil component 2 in actual use, the land pattern on the printed circuit board and the mounting parts 31 and 41 of the terminal fittings 30 and 40 are connected through a solder. At this time, the solder reaches the fillet formation parts 38 and 48 by surface tension to form a solder fillet.

In the present embodiment, it is not essential to short-circuit the one ends of the wires W1 and W2 on the flange part 11 and to short-circuit the other ends thereof on the flange parts 12 but a configuration as in a coil component 3 according to a second modification illustrated in FIG. 4 may be adopted, in which two terminal electrodes E11 and E12 are provided on the flange part 11, two terminal electrodes E21 and E22 are provided on the flange part 12, one ends of the wire W1 and W2 are connected to the terminal electrodes E11 and E12, respectively, and the other ends of the wire W1 and W2 are connected to the terminal electrodes E21 and E22, respectively. In this case, by short-circuiting the terminal electrodes E11 and E12 and short-circuiting the terminal electrodes E21 and E22 on a printed circuit board on which the coil component 3 is mounted, the wires W1 and W2 can be connected in parallel. For example, as illustrated

in FIG. 5, the coil component 3 may be mounted on a mounting area 3a of a printed circuit board having a land pattern 61 connected to a wire 51 and a land pattern 62 connected to a wire 52. When the coil component 3 is mounted on the mounting area 3a, the terminal electrodes E11 and E12 are connected in common to the land pattern 61, and the terminal electrodes E21 and E22 are connected in common to the land pattern 62, with the result that the wires W1 and W2 are connected in parallel.

10 In the present embodiment, the two wires W1 and W2 are wound around the winding core part 13 of the core 10 in multiple turns and in multiple layers.

The following describes in detail the winding structure of the wires W1 and W2.

15 FIG. 6 is a schematic cross-sectional view for explaining a first winding structure of the wires W1 and W2.

The number assigned to each of the wires W1 and W2 in FIG. 6 indicates the number of turns with the terminal electrode E1 (E11, E12) or metal fitting 30 as a winding 20 starting point. The same applies to FIGS. 7 to 14. In the examples described below, the number of turns of the wire W1 and the number of turns of the wire W2 are each set to 36, but not limited thereto.

25 In the first winding structure illustrated in FIG. 6, the wires W1 and W2 constitute three winding layers on the winding core part 13. The three winding layers include a lower layer L1 closest to the winding core part 13, an upper layer L3 farthest from the winding core part 13, and an intermediate layer L2 positioned between the lower layer L1 30 and the upper layer L3. In the example of FIG. 6, the lower layer L1 constitutes the lowermost layer, and the upper layer L3 constitutes the uppermost layer.

35 As illustrated in FIG. 6, the 1st to 3rd, 5th, 6th, 8th, 9th, 11th, 12th, 14th, 15th, 17th, 18th, 20th, 21st, 23rd, 24th, 26th, 27th, 29th, 30th, 32nd, 33rd, 35th and 36th turns of the wire W1 and the 1st turn of the wire W2 are wound in the lower layer L1, the 4th, 7th, 10th, 13th, 16th, 19th, 22nd, 25th, 28th, 31st and 34th turns of the wire W1 and the 2nd, 3rd, 6th, 9th, 12th, 15th, 18th, 21st, 24th, 27th, 30th, 33rd 40 and 36th turns of the wire W2 are wound in the intermediate layer L2, and the 4th, 5th, 7th, 8th, 10th, 11th, 13th, 14th, 16th, 17th, 19th, 20th, 22nd, 23rd, 25th, 26th, 28th, 29th, 31st, 32nd, 34th and 35th turns of the wire W2 are wound in the upper layer L3. As described above, in the first winding structure, the wire W1 is axially continuously wound in the lower layer L1 in an aligned state, the wire W2 is axially continuously wound in the upper layer L3 in an aligned state, and the wires W1 and W2 are alternately wound in the intermediate layer L2.

45 The turns wound in the intermediate layer L2 are each wound along a valley line formed by two adjacent turns wound in the lower layer L1. Similarly, the turns wound in the upper layer L3 are each wound along a valley line formed by two adjacent turns wound in the intermediate 50 layer L2. Specifically, the 4th, 7th, 10th, 13th, 16th, 19th, 22nd, 25th, 28th, 31st and 34th turns of the wire W1 wound in the intermediate layer L2 are each wound along a valley line formed by turns of the wire W1 wound in the lower layer L1 whose turn numbers are smaller by 2 and 1 therethan, and the 6th, 9th, 12th, 15th, 18th, 21st, 24th, 27th, 30th, 33rd and 36th turns of the wire W2 wound in the intermediate layer L2 are each wound along a valley line formed by turns of the wire W1 wound in the lower layer L1 whose turn numbers are smaller by 3 and 1 therethan. 55 Further, the 8th, 11th, 14th, 17th, 20th, 23rd, 26th, 29th, 32nd and 35th turns of the wire W2 wound in the upper layer L3 are each wound along a valley line formed by a turn of

the wire W2 wound in the intermediate layer L2 whose turn number is smaller by 2 therethan and a turn of the wire W1 wound in the intermediate layer L2 whose turn number is smaller by 1 therethan, and the 10th, 13th, 16th, 19th, 22nd, 25th, 28th, 31st and 34th turns of the wire W2 wound in the upper layer L3 are each wound along a valley line formed by a turn of the wire W1 wound in the intermediate layer L2 whose turn number is smaller by 3 therethan and a turn of the wire W2 wound in the intermediate layer L2 whose turn number is smaller by 1 therethan.

More generally, except for the 1st to 4th turns of each of the wires W1 and W2, the i-th turn (i is an integer equal to or larger than 5) and (i-th+1) turn of the wire W1 are wound in the lower layer L1, (i-th+2) turn of the wire W1 and (i-th+1) turn of the wire W2 are wound in the intermediate layer L2, and i-th turn and (i-th+2) turn of the wire W2 are wound in the upper layer L3. Further, (i-th+2) turn of the wire W1 is wound along a valley line formed by the i-th turn and (i-th+1) turn of the wire W1, and (i-th+4) turn of the wire W2 is wound along a valley line formed by (i-th+1) turn and (i-th+3) turn of the wire W1. Furthermore, (i-th+3) turn of the wire W2 is wound along a valley line formed by (i-th+2) turn of the wire W1 and (i-th+1) turn of the wire W2, and (i-th+5) turn of the wire W2 is wound along a valley line formed by (i-th+2) turn of the wire W1 and (i-th+4) turn of the wire W2.

A method for obtaining the first winding structure illustrated in FIG. 6 is as follows. As illustrated in FIG. 7, first, the 1st turns of the respective wires W1 and W2 are wound side by side in the lower layer L1. Then, the 2nd turn of the wire W1 is wound along the 1st turn of the wire W1, and the 2nd turn of the wire W2 is wound along a valley line formed by the 1st turns of the respective wires W1 and W2. Subsequently, the 3rd turn of the wire W1 is wound along the 2nd turn of the wire W1, and the 3rd turn of the wire W2 is wound along a valley line formed by the 1st and 2nd turns of the wire W1. Further, the 4th turn of the wire W1 is wound along a valley line formed by the 2nd and 3rd turns of the wire W1, and the 4th turn of the wire W2 is wound along a valley line formed by the 2nd and 3rd turns of the wire W2. The above-described 1st to 4th turns of the wire W1 and those of the wire W2 collectively constitute a wall for properly winding the 5th and subsequent turns of each of the wires W1 and W2 so as to prevent collapse of the winding.

Subsequently, as illustrated in FIG. 8, the 5th turn of the wire W1 is wound along the 3rd turn of the wire W1, and the 5th turn of the wire W2 is wound along a valley line formed by the 4th turn of the wire W1 and the 3rd turn of the wire W2. Subsequently, the 6th turn of the wire W1 is wound along the 5th turn of the wire W1, and the 6th turn of the wire W2 is wound along a valley line formed by the 3rd and 5th turns of the wire W1. Further, the 7th turn of the wire W1 is wound along a valley line formed by the 5th and 6th turns of the wire W1, and the 7th turn of the wire W2 is wound along a valley line formed by the 4th turn of the wire W1 and the 6th turn of the wire W2.

After that, the winding work is repeatedly performed under the same rule as for the winding work of the three turns including the above-described 5th to 7th turns. That is, by repeatedly forming a winding pattern including the i-th to (i-th+2) turns, the first winding structure having a regular winding structure can be obtained.

As described above, in the first winding structure, the same turns of the wires W1 and W2, except for the 1st turns thereof, are disposed in mutually different winding layers, so that the degree of winding work can be enhanced. This can

prevent an increase in a parasitic capacitance component due to proximity between two turns between which a difference in turn number is large. That is, a parasitic capacitance component generated by two turns between which a difference in turn number is small is mainly connected in series and is thus reduced in value, while a parasitic capacitance component generated by two turns between which a difference in turn number is large is mainly connected in parallel and thus tends to be increased in value. In the first winding structure, a difference in turn number between adjacent turns is suppressed to 3 at maximum, so that an increase in the parasitic capacitance component is suppressed, thus allowing an increase in resonance frequency.

FIG. 9 is a schematic cross-sectional view for explaining a second winding structure of the wires W1 and W2.

In the second winding structure illustrated in FIG. 9, the wires W1 and W2 constitute four winding layers on the winding core part 13. The four winding layers include, in the order of proximity from the winding core part 13, a lower layer L1, a first intermediate layer L2a, a second intermediate layer L2b and an upper layer L3.

As illustrated in FIG. 9, the 1st to 4th, 6th, 8th, 9th, 12th, 13th, 16th, 17th, 20th, 21st, 24th, 25th, 28th, 29th, 32nd, 33rd and 36th turns of the wire W1 and the 1st turn of the wire W2 are wound in the lower layer L1, the 5th, 10th, 14th, 18th, 22nd, 26th, 30th and 34th turns of the wire W1 and the 2nd to 4th, 9th, 13th, 17th, 21st, 25th, 29th and 33rd turns of the wire W2 are wound in the first intermediate layer L2a, the 7th, 11th, 15th, 19th, 23rd, 27th, 31st and 35th turns of the wire W1 and the 5th, 6th, 10th, 14th, 18th, 22nd, 26th, 30th and 34th turns of the wire W2 are wound in the second intermediate layer L2b, and the 7th, 8th, 11th, 12th, 15th, 16th, 19th, 20th, 23rd, 24th, 27th, 28th, 31st, 32nd, 35th and 36th turns of the wire W2 are wound in the upper layer L3.

As described above, in the second winding structure, the wire W1 is axially continuously wound in the lower layer L1 in an aligned state, the wire W2 is axially continuously wound in the upper layer L3 in an aligned state, and the wires W1 and W2 are alternately axially wound in each of the first and second intermediate layers L2a and L2b.

The turns wound in the first intermediate layer L2a are each wound along a valley line formed by two adjacent turns wound in the lower layer L1. Similarly, the turns wound in the second intermediate layer L2b are each wound along a valley line formed by two adjacent turns wound in the first intermediate layer L2a. Further, the turns wound in the upper layer L3 are each wound along a valley line formed by two adjacent turns wound in the second intermediate layer L2b. Specifically, the 14th, 18th, 22nd, 26th, 30th and 34th turns of the wire W1 wound in the first intermediate layer L2a are each wound along a valley line formed by turns of the wire W1 wound in the lower layer L1 whose turn numbers are smaller by 5 and 2 therethan, and the 13th, 17th, 21st, 25th, 29th and 33rd turns of the wire W2 wound in the first intermediate layer L2a are each wound along a valley line formed by turns of the wire W1 wound in the lower layer L1 whose turn numbers are smaller by 5 and 4 therethan. Further, the 11th, 15th, 19th, 23rd, 27th, 31st and 35th turns of the wire W1 wound in the second intermediate layer L2b are each wound along a valley line formed by a turn of the wire W1 wound in the first intermediate layer L2a whose turn number is smaller by 1 therethan and a turn of the wire W2 wound in the first intermediate layer L2a whose turn number is smaller by 2 therethan, and the 14th, 18th, 22nd, 26th, 30th and 34th turns of the wire W2 wound in the second intermediate layer L2b are each wound along a valley line formed by a turn of the wire W1 wound in the

first intermediate layer L_{2a} whose turn number is smaller by 4 than that of the wire W₂ wound in the first intermediate layer L_{2a} whose turn number is smaller by 1 than that of the wire W₂. Further, the 8th, 12th, 16th, 20th, 24th, 28th, 32nd and 36th turns of the wire W₂ wound in the upper layer L₃ are each wound along a valley line formed by a turn of the wire W₂ wound in the second intermediate layer L_{2b} whose turn number is smaller by 2 than that of the wire W₁ wound in the second intermediate layer L_{2b} whose turn number is smaller by 1 than that of the wire W₁, and the 11th, 15th, 19th, 23rd, 27th, 31st and 35th turns of the wire W₂ wound in the upper layer L₃ are each wound along a valley line formed by a turn of the wire W₁ wound in the second intermediate layer L_{2b} whose turn number is smaller by 4 than that of the wire W₂ wound in the second intermediate layer L_{2b} whose turn number is smaller by 1 than that of the wire W₁.

More generally, except for the 1st to 7th turns of each of the wires W₁ and W₂, the i-th turn (i is an integer equal to or larger than 8) and (i-th+1) turn of the wire W₁ are wound in the lower layer L₁, (i-th+2) turn of the wire W₁ and (i-th+1) turn of the wire W₂ are wound in the first intermediate layer L_{2a}, (i-th+3) turn of the wire W₁ and (i-th+2) turn of the wire W₂ are wound in the second intermediate layer L_{2b}, and i-th turn and (i-th+3) turn of the wire W₂ are wound in the upper layer L₃. Further, (i-th+5) turn of the wire W₂ is wound along a valley line formed by the i-th turn and (i-th+1) turn of the wire W₁, and (i-th+6) turn of the wire W₁ is wound along a valley line formed by (i-th+1) turn and (i-th+4) turn of the wire W₁. Further, (i-th+3) turn of the wire W₁ is wound along a valley line formed by (i-th+2) turn of the wire W₁ and (i-th+1) turn of the wire W₂, and (i-th+6) turn of the wire W₂ is wound along a valley line formed by (i-th+2) turn of the wire W₁ and (i-th+5) turn of the wire W₂. Further, (i-th+4) turn of the wire W₂ is wound along a valley line formed by (i-th+3) turn of the wire W₁ and (i-th+2) turn of the wire W₂, and (i-th+7) turn of the wire W₂ is wound along a valley line formed by (i-th+3) turn of the wire W₁ and (i-th+6) turn of the wire W₂.

A method for obtaining the second winding structure illustrated in FIG. 9 is as follows. As illustrated in FIG. 10, first, the 1st turns of the respective wires W₁ and W₂ are wound side by side in the lower layer L₁. Then, the 2nd turn of the wire W₁ is wound along the 1st turn of the wire W₁, and the 2nd turn of the wire W₂ is wound along a valley line formed by the 1st turns of the respective wires W₁ and W₂. Subsequently, the 3rd turn of the wire W₁ is wound along the 2nd turn of the wire W₁, and the 3rd turn of the wire W₂ is wound along a valley line formed by the 1st and 2nd turns of the wire W₁. Subsequently, the 4th turn of the wire W₁ is wound along the 3rd turn of the wire W₁, and the 4th turn of the wire W₂ is wound along a valley line formed by the 2nd and 3rd turns of the wire W₁. Subsequently, the 5th turn of the wire W₁ is wound along a valley line formed by the 3rd and 4th turns of the wire W₁, and the 5th turn of the wire W₂ is wound along a valley line formed by the 2nd and 3rd turns of the wire W₂. Subsequently, the 6th turn of the wire W₁ is wound along the 4th turn of the wire W₁, and the 6th turn of the wire W₂ is wound along a valley line formed by the 3rd and 4th turns of the wire W₂. Further, the 7th turn of the wire W₁ is wound along a valley line formed by the 5th turn of the wire W₁ and the 4th turn of the wire W₂, and the 7th turn of the wire W₂ is wound along a valley line formed by the 5th and 6th turns of the wire W₂. The above-described 1st to 7th turns of the wire W₁ and those of the wire W₂ collectively constitute a wall for properly winding the 8th and subsequent turns of each of the wires W₁ and W₂ so as to prevent collapse of the winding. In the

turns constituting the wall, the number of turns wound in the lower layer L₁ is larger by 2 than the number of turns wound in the first intermediate layer L_{2a}, so that collapse of the winding is unlikely to occur in the subsequent winding work.

Then, as illustrated in FIG. 11, the 8th turn of the wire W₁ is wound along the 6th turn of the wire W₁, and the 8th turn of the wire W₂ is wound along a valley line formed by the 7th turn of the wire W₁ and the 6th turn of the wire W₂. Subsequently, the 9th turn of the wire W₁ is wound along the 8th turn of the wire W₁, and the 9th turn of the wire W₂ is wound along a valley line formed by the 4th and 6th turns of the wire W₁. Subsequently, the 10th turn of the wire W₁ is wound along a valley line formed by the 6th and 8th turns of the wire W₁, and the 10th turn of the wire W₂ is wound along a valley line formed by the 5th turn of the wire W₁ and the 9th turn of the wire W₂. Further, the 11th turn of the wire W₁ is wound along a valley line formed by the 10th turn of the wire W₁ and the 9th turn of the wire W₂, and the 11th turn of the wire W₂ is wound along a valley line formed by the 7th turn of the wire W₁ and the 10th turn of the wire W₂.

After that, the winding work is repeatedly performed under the same rule as for the winding work of the four turns including the above-described 8th to 11th turns. That is, by repeatedly forming a winding pattern including the i-th to (i-th+3) turns, the second winding structure having a regular winding structure can be obtained.

As described above, in the second winding structure as well, the same turns of the wires W₁ and W₂, except for the 1st turns thereof, are disposed in mutually different winding layers, so that the degree of freedom of winding work can be enhanced to make it possible to prevent an increase of parasitic capacitance component. Specifically, in the second winding structure, a difference in turn number between adjacent turns is suppressed to 5 at maximum, so that an increase of parasitic capacitance component is suppressed, thus increasing resonance frequency. In addition, the wires W₁ and W₂ constitute four winding layers, thus making it possible to further reduce the axial length of the winding core part 13.

FIG. 12 is a schematic cross-sectional view for explaining a third winding structure of the wires W₁ and W₂.

In the third winding structure illustrated in FIG. 12, the wires W₁ and W₂ constitute four winding layers on the winding core part 13 as in the second winding structure.

The odd-numbered turns and 2nd turn of the wire W₁ and the 1st turn of the wire W₂ are wound in the lower layer L₁. The even-numbered turns of the wire W₁, except for the 2nd turn thereof, and the 2nd and 3rd turns of the wire W₂ are wound in the first intermediate layer L_{2a}. The odd-numbered turns and 4th turn of the wire W₂, except for the 1st and 3rd turns thereof are wound in the second intermediate layer L_{2b}. The odd-numbered turns of the wire W₂, except for the 2nd and 4th turns thereof are wound in the upper layer L₃. As described above, in the third winding structure, the wire W₁ is axially continuously wound in the lower layer L₁ and first intermediate layer L_{2a} in an aligned state, and the wire W₂ is axially continuously wound in the upper layer L₃ and second intermediate layer L_{2b} in an aligned state.

The turns wound in the first intermediate layer L_{2a} are each wound along a valley line formed by two adjacent turns wound in the lower layer L₁. Similarly, the turns wound in the second intermediate layer L_{2b} are each wound along a valley line formed by two adjacent turns wound in the first intermediate layer L_{2a}. Further, the turns wound in the upper layer L₃ are each wound along a valley line formed by two adjacent turns wound in the second intermediate layer

11

L2b. Specifically, the 6th to 36th turns of the wire W1 wound in the first intermediate layer L2a are each wound along a valley line formed by turns of the wire W1 wound in the lower layer L1 whose turn numbers are smaller by 3 and 1 therethan. Further, the 7th to 35th turns of the wire W2 wound in the second intermediate layer L2b are each wound along a valley line formed by turns of the wire W1 wound in the first intermediate layer L2a whose turn numbers are smaller by 3 and 1 therethan. Furthermore, the 8th to 36th turns of the wire W2 wound in the upper layer L3 are each wound along a valley line formed by turns of the wire W2 wound in the second intermediate layer L2b whose turn number is smaller by 3 and 1 therethan.

More generally, except for the 1st to 4th turns of each of the wires W1 and W2, the i-th turn (i is an integer equal to or larger than 5) and (i-th+2) turn of the wire W1 are wound in the lower layer L1, (i-th+1) turn and (i-th+3) turn of the wire W1 are wound in the first intermediate layer L2a, i-th turn and (i-th+2) turn of the wire W2 are wound in the second intermediate layer L2b, and (i-th+1) turn and (i-th+3) turn of the wire W2 are wound in the upper layer L3. Further, (i-th+3) turn of the wire W1 is wound along a valley line formed by the i-th turn and (i-th+2) turn of the wire W1, and (i-th+5) turn of the wire W1 is wound along a valley line formed by (i-th+2) turn and (i-th+4) turn of the wire W1. Further, (i-th+4) turn of the wire W2 is wound along a valley line formed by (i-th+1) turn and (i-th+3) turn of the wire W1, and (i-th+6) turn of the wire W2 is wound along a valley line formed by (i-th+3) turn and (i-th+5) turn of the wire W1. Further, (i-th+3) turn of the wire W2 is wound along a valley line formed by the i-th turn and (i-th+2) turn of the wire W2, and (i-th+5) turn of the wire W2 is wound along a valley line formed by (i-th+2) turn and (i-th+4) turn of the wire W2.

A method for obtaining the third winding structure illustrated in FIG. 12 is as follows. As illustrated in FIG. 13, first, the 1st turns of the respective wires W1 and W2 are wound side by side in the lower layer L1. Then, the 2nd turn of the wire W1 is wound along the 1st turn of the wire W1, and the 2nd turn of the wire W2 is wound along a valley line formed by the 1st turns of the respective wires W1 and W2. Subsequently, the 3rd turn of the wire W1 is wound along the 2nd turn of the wire W1, and the 3rd turn of the wire W2 is wound along a valley line formed by the 1st and 2nd turns of the wire W1. Subsequently, the 4th turn of the wire W1 is wound along a valley line formed by the 2nd and 3rd turns of the wire W1, and the 4th turn of the wire W2 is wound along a valley line formed by the 2nd and 3rd turns of the wire W2. The above-described 1st to 4th turns of the wire W1 and those of the wire W2 collectively constitute a wall for properly winding the 5th and subsequent turns of each of the wires W1 and W2 so as to prevent collapse of the winding.

Subsequently, as illustrated in FIG. 14, the 5th turn of the wire W1 is wound along the 3rd turn of the wire W1, and the 5th turn of the wire W2 is wound along a valley line formed by the 4th turn of the wire W1 and the 3rd turn of the wire W2. Subsequently, the 6th turn of the wire W1 is wound along a valley line formed by the 3rd and 5th turns of the wire W1, and the 6th turn of the wire W2 is wound along a valley line formed by the 4th and 5th turns of the wire W2. Subsequently, the 7th turn of the wire W1 is wound along the 5th turn of the wire W1, and the 7th turn of the wire W2 is wound along a valley line formed by the 4th and 6th turns of the wire W1. Further, the 8th turn of the wire W1 is wound along a valley line formed by the 5th and 7th turns

12

of the wire W1, and the 8th turn of the wire W2 is wound along a valley line formed by the 5th and 7th turns of the wire W2.

After that, the winding work is repeatedly performed under the same rule as for the winding work of the four turns including the above-described 5th to 8th turns. That is, by repeatedly forming a winding pattern including the i-th to (i-th+3) turns, the third winding structure having a regular winding structure can be obtained.

As described above, in the third winding structure as well, the same turns of the wires W1 and W2, except for the 1st turns thereof, are disposed in mutually different winding layers, so that the degree of winding work can be enhanced to make it possible to prevent an increase of parasitic capacitance component. Specifically, in the third winding structure, a difference in turn number between adjacent turns is suppressed to 3 at maximum, so that an increase of parasitic capacitance component is suppressed, thus allowing an increase in resonance frequency. In addition, the wires W1 and W2 constitute four winding layers, thus making it possible to further reduce the axial length of the winding core part 13.

It is apparent that the present invention is not limited to the above embodiments, but may be modified and changed without departing from the scope and spirit of the invention.

What is claimed is:

1. A coil component comprising:

a winding core part; and

first and second wires wound around the winding core part, wherein the first and second wires constitute at least three winding layers on the winding core part, and wherein same turns of the first and second wires are positioned in mutually different winding layers over a plurality of turns,

wherein the at least three winding layers include a lower layer closest to the winding core part, an upper layer farther away from the winding core part than the lower layer, and at least one intermediate layer positioned between the lower and upper layers,

wherein the lower layer includes the first wire, wherein the upper layer includes the second wire, wherein the intermediate layer includes the first and second wires in a mixed manner,

wherein an i-th turn (i is an integer equal to or larger than 5) and an (i-th+1) turn of the first wire are wound in the lower layer,

wherein an (i-th+2) turn of the first wire and an (i-th+1) turn of the second wire are wound in the intermediate layer, and

wherein an i-th turn and a (i-th+2) turn of the second wire are wound in the upper layer.

2. The coil component as claimed in claim 1,

wherein the first wire is continuously wound in the lower layer in an aligned state, wherein the second wire is continuously wound in the upper layer in an aligned state, and

wherein the first and second wires are alternately wound in the intermediate layer.

3. The coil component as claimed in claim 1, wherein the (i-th+2) turn of the first wire is wound along a valley line formed by the i-th turn and the (i-th+1) turn of the first wire.

4. The coil component as claimed in claim 3,

wherein an (i-th+3) turn of the second wire is wound along a valley line formed by the (i-th+2) turn of the first wire and the (i-th+1) turn of the second wire, and

13

wherein an (i-th+4) turn of the second wire is wound along a valley line formed by the (i-th+1) turn and a (i-th+3) turn of the first wire.

5. The coil component as claimed in claim 1, wherein the intermediate layer includes a first intermediate layer positioned on the lower layer side and a second intermediate layer positioned on the upper layer side, whereby the first and second wires constitute at least four winding layers.

6. The coil component as claimed in claim 5, wherein the first wire is continuously wound in the lower

layer in an aligned state, wherein the second wire is continuously wound in the upper layer in an aligned state, and wherein the first and second wires are alternately wound

15 in the first and second intermediate layers.

7. The coil component as claimed in claim 6, wherein an i-th turn (i is an integer equal to or larger than 8) and an (i-th+1) turn of the first wire are wound in the lower layer,

wherein an (i-th+2) turn of the first wire and an (i-th+1) turn of the second wire are wound in the first intermediate layer,

wherein an (i-th+3) turn of the first wire and an (i-th+2) turn of the second wire are wound in the second intermediate layer, and

wherein an i-th turn and an (i-th+3) turn of the second wire are wound in the upper layer.

8. The coil component as claimed in claim 7, wherein the (i-th+3) turn of the first wire is wound along a valley line formed by the (i-th+2) turn of the first wire and the (i-th+1) turn of the second wire.

9. The coil component as claimed in claim 8, wherein an (i-th+4) turn of the second wire is wound

35 along a valley line formed by the (i-th+3) turn of the first wire and the (i-th+2) turn of the second wire,

wherein an (i-th+5) turn of the second wire is wound along a valley line formed by the i-th turn and the (i-th+1) turn of the first wire, and

wherein an (i-th+6) turn of the second wire is wound along a valley line formed by the (i-th+2) turn of the first wire and the (i-th+5) turn of the second wire.

10. The coil component as claimed in claim 5, wherein the first wire is continuously wound in the lower

45 layer and first intermediate layer in an aligned state, and wherein the second wire is continuously wound in the upper layer and second intermediate layer in an aligned state.

11. The coil component as claimed in claim 10, wherein an i-th turn (i is an integer equal to or larger than 5) and an (i-th+2) turn of the first wire are wound in the lower layer,

wherein an (i-th+1) turn and an (i-th+3) turn of the first wire are wound in the first intermediate layer, wherein an i-th turn and an (i-th+2) turn of the second

55 wire are wound in the second intermediate layer, and wherein an (i-th+1) turn and an (i-th+3) turn of the second wire are wound in the upper layer.

12. The coil component as claimed in claim 11, wherein the (i-th+3) turn of the first wire is wound along

65 a valley line formed by the i-th turn and the (i-th+2) turn of the first wire, and wherein the (i-th+3) turn of the second wire is wound

along a valley line formed by the i-th turn and the (i-th+2) turn of the second wire.

14

13. The coil component as claimed in claim 12, wherein an (i-th+4) turn of the second wire is wound along a valley line formed by the (i-th+1) turn and the (i-th+3) turn of the first wire, and wherein an (i-th+5) turn of the second wire is wound along a valley line formed by the (i-th+2) turn and the (i-th+4) turn of the second wire.

14. The coil component as claimed in claim 1, further comprising:

a flange part; and a terminal electrode provided on the flange part and connected with one ends of the first and second wires, wherein the one ends of the first and second wires are short-circuited through the terminal electrode.

15. A coil component comprising:

a winding core part;

a flange part;

a terminal electrode provided on the flange part; and first and second wires wound around the winding core

20 part,

wherein one ends of the first and second wire are connected to the terminal electrode,

wherein each of the first and second wires has first, second, and third turns counting from the one end,

wherein the first turn of the second wire, the first turn of the first wire, the second turn of the first wire, and the third turn of the first wire are wound in this order around the winding core part in an aligned state,

wherein the second turn of the second wire is wound around a valley line formed by the first turn of the second wire and the first turn of the first wire, and wherein the third turn of the second wire is wound around a valley line formed by the first turn of the first wire and the second turn of the first wire,

wherein each of the first and second wires further has a fourth turn counting from the one end

wherein the fourth turn of the first wire is wound around a valley line formed by the second turn of the first wire and the third turn of the first wire, and

wherein the fourth turn of the second wire is wound around a valley line formed by the second turn of the second wire and the third turn of the second wire.

16. The coil component as claimed in claim 15, wherein each of the first and second wires further has

40 fourth and fifth turns counting from the one end, wherein the fourth turn of the first wire is wound adjacent to the third turn of the first wire around the winding core part,

wherein the fourth turn of the second wire is wound around a valley line formed by the second turn of the first wire and the third turn of the first wire,

wherein the fifth turn of the first wire is wound around a valley line formed by the third turn of the first wire and the fourth turn of the first wire, and

wherein the fifth turn of the second wire is wound around a valley line formed by the second turn of the second wire and the third turn of the second wire.

17. A coil component comprising:

a winding core part; and

first and second wires wound around the winding core

part,

wherein the first and second wires constitute three winding layers including a first layer closest to the winding core part, a second layer positioned on the first layer, and a third layer positioned on the second layer,

wherein the first wire is continuously wound in the first

layer in an aligned state,

15

wherein the second wire is continuously wound in the third layer in an aligned state, and wherein the first and second wires are alternately wound in the second layer such that each turn of the first wire in the second layer is sandwiched between two turns of the second wire in the second layer, and such that each turn of the second wire in the second layer is sandwiched between two turns of the first wire in the second layer.

18. The coil component as claimed in claim **17**, wherein the first wire has fifth, sixth, and seventh turns, wherein each of the fifth and sixth turns of the first wire is located at the first layer, and wherein the seventh turn of the first wire is located at the second layer.

19. The coil component as claimed in claim **18**, wherein the second wire has sixth, seventh, and eighth turns,

5

10

15

16

wherein each of the seventh and eighth turns of the second wire is located at the third layer, and wherein the sixth turn of the second wire is located at the second layer.

20. The coil component as claimed in claim **19**, wherein the second wire further has ninth, tenth, and eleventh turns,

wherein each of the tenth and eleventh turns of the second wire is located at the third layer such that the eighth and tenth turns of the second wire are adjacent to each other, and

wherein the ninth turn of the second wire is located at the second layer such that the seventh turn of the first wire is sandwiched between the sixth and ninth turns of the second wire.
